UNITED STATES PATENT OFFICE.

OLIVER S. GARRETSON, OF BUFFALO, NEW YORK.

EXTENSION-TABLE SLIDE.

SPECIFICATION forming part of Letters Patent No. 229,037, dated June 22, 1880.

Application filed December 29, 1879.

To all whom it may concern:

Be it known that I, OLIVER S. GARRETSON, of the city of Buffalo, in the county of Erie and State of New York, have invented new 5 and useful Improvements in Extension-Table Slides, of which the following is a specification, reference being had to the accompanying drawings.

This invention relates more especially to 10 that class of table-slides in which the wings and grooves are constructed in the form of a cross laid on its side; and it has for its object to render such slides more durable and more easy and uniform in their operation.

15 My invention consists, to that end, of a cross-slide constructed with two angular ribs arranged respectively on the upper and lower side of the slide in the angle of its wings, whereby the sharp edges on the wooden slide-bars are avoided and the operation of the 20 slides is rendered more easy and uniform.

In the accompanying drawings, Figure 1 is 25 an end view of my improved slides. Fig. 2 is an end view of one of the slide-bars. Fig. 3 is a similar view of an ordinary cross slide-bar. Fig. 4 is a perspective view of one of my improved metallic slides. Fig. 5 is a horizontal section of the slide-bars provided with my improvement.

30 Like letters of reference refer to similar parts in the several figures.

A represents the wooden slide-bars, and B the metallic slides, secured in the grooves of 35 the slide-bars by fastening-pins e. The slides B and the grooves d of the slide-bars are constructed in the form of a cross laid on its side, the wings of the slides being arranged at right angles to each other, or at any other suitable angle, as may be preferred.

40 The wings e e of the slide, which are stationary within the groove of the slide-bar, are made somewhat thicker than the wings f f of the same slide, which are movable within the groove, so that the wings e e can be tightly driven into the groove of one slide-bar, while the wings f f will work freely in the groove of the opposite slide-bar.

g g are angular ribs arranged in the angles formed by the wings e and f on the upper and lower sides of the slides, the ridge or apex of 50 the ribs g being in the plane of contact of the two adjacent slide-bars. The angle of the rib g is preferably arranged to correspond with the angle of the wings e f, so that the grooves for the reception of the ribs g can be formed in 55 the slide-bars by the same cuts which form the grooves for the reception of the wings e f, as indicated by the dotted lines in Fig. 2. The ribs g take off the sharp edge h of the ordinary cross-slide, (represented in Fig. 3,) which 60 edge is very thin and sharp, and frequently becomes broken off or bruised or bent in making or handling the slides.

When a downward pressure is applied to the ordinary slide-bar the straight incline, terminating in the edge h, tends to wedge the bars together, thereby interfering with the free movement of the slides, while in my improved slide this thrust is received and counteracted by the rib or shoulder g, and the wedging or 65 cramping of the slides is thereby entirely avoided.

70 By the use of my improved slide the free and unobstructed movement of the bars is insured, and the edges of the grooves are made 75 so blunt that no splitting off or bruising of the edges can occur, thereby rendering the slides very durable.

As shown in Fig. 4, a portion of the running 80 or thin wings f of each slide is cut off to form a shoulder, which strikes against the stop-pins i, secured in the grooves d of the slide-bars, and arrests the movement of the slides in the ordinary manner.

I claim as my invention—
85 A table-slide made in the form of a cross, and constructed with ribs g on its upper and lower sides in the angles of its wings, substantially as set forth.

OLIVER S. GARRETSON.
